UNITED STATES PATENT OFFICE.

JOHN A. PIKE, OF LOS ANGELES, CALIFORNIA.

HAMMER CLAW.

Application filed May 23, 1927. Serial No. 193,503.

My invention relates to carpenters' tools and more particularly to an improved claw-hammer.

As generally made the claw part of a claw hammer is formed in such a manner that when nails are hard to pull their heads often crumple and slip through the claw so that some other means must be employed to draw them. This happens more frequently with 10 the modern wire nails in common use than was the case with the old fashioned cut nails.

The primary object of my invention is to provide an improved claw hammer having its claw equipped with flanges which will engage an exceptionally large portion of a nail head, in a manner to prevent the crumpling thereof, and will insure efficient operation in the pulling of nails.

Other objects and advantages will appear 20 hereinafter and while I show herewith and will describe a preferred form of construction, I desire it to be understood that I do not confine my invention to such preferred form but that various changes and adaptations 25 may be made therein without departing from the spirit of my invention as herein-after claimed.

Referring to the drawings which accompany 30 this specification and form a part thereof,

Fig. 1 is a side view of a hammer having the features embodied in my invention.

Fig. 2 is a view of the hammer shown in Fig. 1 as seen looking at the handle end there- 35 of.

Fig. 3 is a view, similar to Fig. 2, showing the hammer in position for pulling a nail and the claw thereof partly broken away to show its operation when engaging a nail 40 head.

Fig. 4 is a side view of the hammer head, in position for pulling a nail, one side of the claw and part of the head being shown broken away, to further illustrate the operation 45 of the hammer when used as a nail puller.

The hammer, as a whole, may be any type of claw hammer, with the usual form of head 10 and handle 11, except that a groove 12 of 50 rectangular cross-section, which increases in

depth from the end of the claw 13 toward the eye 14 of the hammer and increases in width in a reverse direction, is formed in the under or concave side of the claw. The depth and width of the groove are varied so as to produce equal and opposite flanges 15 on opposite sides of the usual cleft 16, which flanges decrease in width and in thickness from their beginning near the end of the claw toward the eye of the hammer. The claw is thus adapted 55 for pulling nails of all sizes, larger ones being engaged toward the end of the claw, where flanges 15 are thicker, and smaller ones toward the eye, where flanges 15 are thinner.

It will be observed that the bottom of the 60 groove 12 is flat or rather that it lies in a curved plane, the elements of which taken transversely of the hammer claw, are parallel to like elements of the curved plane forming the outer surface of the claw, so that flanges 65 15 are of uniform thickness on every transverse line. This arrangement of the groove provides uniform pressure against the under side of the head of the nail being pulled and therefore overcomes the tendency to deflect 70 upwardly the edge portions of the head of the nail, thus reducing to a minimum the danger of bending the head out of shape and dragging the hammer free therefrom without extracting the nail. The edge portions of the 75 head of a nail being pulled, may also abut against the straight sides of the groove and be thereby further safeguarded against distortion.

The operation of my improved claw hammer in pulling a nail is clearly indicated in 80 Figs. 3 and 4. Flanges 15 of the claw engage the underside of the nail-head 17 squarely and close to the shank 18 thereof so that there is an unusually large contact surface 85 between the nail head and flanges 15 and also a uniform pulling strain on that contact surface which does not tend to crumple the sides of the nail head as the beveled faces of the usual claw cleft do.

Having thus illustrated and described my invention, I claim:

1. A claw hammer having a groove in the concave side of the claw thereof which produces flanges of varying width and thick- 100

ness on either side of the cleft thereof, said groove being flat from side to side thereof and the flanges wherein said groove is formed being adapted to engage directly against all portions of the under surface of the head of a wire nail from its shank to its outer edges.

2. A claw hammer having between the claws thereof a groove which is rectangular

in cross-section, the bottom of said groove being adapted to engage the under surface ¹⁰ of the head of a nail being pulled, the side portions of said groove forming vertical surfaces against which opposite sides of the head of such nail may abut.

JOHN A. PIKE.
